CLAIM

The ornamental design for a remote control for video management, as shown and described.

DESCRIPTION

FIG. 1 is a top perspective view showing a remote control design according to an embodiment;

FIG. 2 is a front view of the remote control for video management design of FIG. 1;

FIG. 3 is a back view of the remote control for video management design of FIG. 1;

FIG. 4 is a side view of the remote control for video management design of FIG. 1;

FIG. 5 is another side view of the remote control for video management design of FIG. 1;

FIG. 6 is a bottom view of the remote control for video management design of FIG. 1; and,

FIG. 7 is a top view of the remote control for video management design of FIG. 1.

The broken lines of the preceding FIGURES illustrate a boundary and, further, the broken lines are for illustration only and form no part of the claimed design.
